UNITED STATES PATENT OFFICE

135,580

DESIGN FOR A GAME BOARD

Oscar T. Querness, Los Angeles, Calif.

Application February 16, 1943, Serial No. 109,556

Term of patent 14 years

To all whom it may concern:

Be it known that I, Oscar T. Querness, a citizen of the United States, residing at Los Angeles, in the county of Los Angeles, State of California, have invented a new, original, and ornamental Design for a Game Board, of which the following is a specification, reference being had to the accompanying drawing, forming a part thereof, in which:

Fig. 1 is a top plan view of a game board, showing my new design; and,

Fig. 2 is a sectional view thereof, taken through 2—2 of Fig. 1.

The parallel vertical lines shown in the pockets 1 designate the color red, while the parallel horizontal broken lines of the holes 2 designate a silver color.

I claim:

The ornamental design for a game board, substantially as shown and described.

OSCAR T. QUERNESS.
